UNITED STATES PATENT OFFICE.

AMBROSE FLEMING, OF WASHINGTON, DISTRICT OF COLUMBIA.

MAGAZINE-FED PENCIL.

Application filed March 16, 1923. Serial No. 625,557.

To all whom it may concern:

Be it known that I, AMBROSE FLEMING, a citizen of the United States, residing at Washington, in the District of Columbia, 5 have invented certain new and useful Improvements in Magazine-Fed Pencils, of which the following is a specification.

My present invention has reference to improvements in that class of writing devices 10 in which is included a pencil carrying end having the leads so contained and arranged whereby a new lead can be readily fed into position and forced out of the holder or casting body by suitable means operable internally of the body.

My present invention is more especially 20 designed for providing certain improved features to that type of pencil holder and lead containing and feeding means disclosed 20 in my patent for pen and pencil holder, issued June 21, 1921, No. 1,382,071.

In my said application, the pencil holder includes a magazine adapted for containing the leads in such annular relation that the 25 said leads are practically automatically and individually fed into position for being moved forward as they are used, by a suitable plunger device, finger operable from the outside of the holder.

From practical experience with a lead pencil holder constructed along the lines shown in my aforesaid Letters Patent, I have found that, while the operative parts serve to accomplish the results desired and 35 explained in my said Letters Patent when properly operated, if the adjustment or set of the parts is not fully or accurately effected, there is more or less danger of an improper feed of the leads forward, or breaking 40 of the leads, as they are caused to pass from their magazine held position in place for being engaged by the plunger or pusher devices provided for dropping the selected ones of the leads into the desired point projected or writing condition.

My present invention primarily seeks to provide certain improvements to the lead holding and positioning devices shown in my other application mentioned, whereby a 50 proper adjustment or setting of the parts must be effected before a new lead can be brought into place from the magazine position, for being engaged by the element that feeds the lead out, as it is used up; or in other words, provision is made whereby it will be impossible to cause any movement

of the nest of leads to bring a new one of the leads in position for being fed out, or broken, by an improper or complete adjustment of the devices that provide for the 60 dropping of a new lead into position for being received by the lead holder and for feeding out the said lead for projecting the desired pencil point.

Another feature of my present invention, 65 is embodied in the manner in which the several parts are adapted for cooperative connection, designed for being relatively economically and expeditiously made in quantities and for being readily assembled for 70 use without the need of specially skilled labor.

In its more complete nature, my present invention seeks to provide a simple, compact, easily assembled and positive coaction 75 of the parts that constitute the pencil holder and certain details of construction and arrangement of such parts, all of which will be hereinafter fully explained, specifically 80 pointed out in the appended claims and illustrated in the accompanying drawings, in which:

Figure 1 is a perspective view of a pencil in which is embodied my invention and which illustrates the manner in which it is 85 manipulated for feeding the lead plunger or expelling element forward or backward, as desired.

Figure 2 is a longitudinal section of the 90 magazine end of my improved construction of writing device, taken substantially on the line 2—2 on Figure 3.

Figures 3 and 4 are cross sections taken 95 on the lines 3—3 and 4—4 on Figure 2, looking in the direction of the arrows.

Figure 5 is a side elevation, partly in longitudinal section, of the combined magazine or lead carrier and the lead ejector controlling casing hereinafter described.

Figure 6 is a plan view of the shiftable 100 closure or gate for regulating the drop of the leads from the magazine into the lead receiver and holder.

Figure 7 is a plan view of the lead receiver and holder.

Briefly stated my present invention comprises an outer casing or shell, one end of which may be, if desired, equipped with a fountain pen, as shown in my patent aforesaid, while the other end is especially adapted to serve as a lead pencil, as is clearly indicated in Figures 1 and 2 of the drawings.

The lead pencil carrier, the pencil ejecting elements and the controlling means that co-operate with the said ejecting elements are shown in Figure 2 as assembled and in their operative connection within the casing, and referring now more particularly to the details of construction, 1 designates a casing, in practice similar in size to the conventional fountain pen casing and preferably made of like material.

At one end, the casing 1 is formed with an internal seat adapted for tightly receiving a bushing 2, which latter constitutes a bearing for an elongated sleeve 30 that constitutes a part of the taper cap 3 through which the pencil point is projected and which, in my present form of pencil, constitutes the turning or adjusting member, since by rotating the said member in one way or the other, the lead ejecting and the lead magazine positioning means are controlled, as will herein-after be fully explained.

4 designates a combined leads container or magazine and feed control for moving the pencil plunger or ejecting element 5, and, in practice, the said parts are as a single member, since the magazine is a tube 40 provided with a series of radially directed V-shaped partition ribs 41 that provide a series of longitudinal pockets or chambers 42, in practice of a suitable length for receiving the series of pencil leads 7 which, after having been placed within the magazine, are maintained in a desired condition ready, at predetermined times, to be fed in position to drop into the lead receiver or holder 8, shown in detail in Figure 7.

By referring to Figure 7, it will be noticed the holder includes a trough-like portion 81 always retained in a relatively fixed position by a pin 9. The turned up end 50 of the pencil ejecting element or plunger 5 passes radially through the elongated slot 82 in the rear tubular extension 83 of the said receiver or holder, as is clearly shown in Figures 2 and 3 and as presently further explained.

The feed control is in the nature of a tube 6 which is of the same diameter as the tube 40, to one end of which it is fixedly joined by a washer 60 which divides the leads magazine and the feed control and which also serves as a bearing and stop device for the rotary gate or closure device 12 that holds the several leads in the magazine pocket and which is shown in detail in Figure 6.

The feed control tube 6 has an internal screw 61 of very slow pitch that extends lengthwise thereof with which the upturned end 50 of the ejector 5 engages, the engagement thereof being such that, as the tube 6, together with the tube 40 is turned in either direction, in the manner presently explained, the ejector 5 is moved forwardly for feeding out the lead ahead of it, or for being returned to its rearmost position, when it is desired

to drop another lead into the receiver or holder, it being understood that as the tubes 40 and 6 are turned, rotation is imparted to the cut off or gate or closure device 12, the rotative movement of which, it should be here stated, is relatively very slow as compared with the rotation of the tubes 4 and 6, the reason for which will be presently fully explained.

14 designates a sleeve that is tightly held within the casing 1 and which constitutes an inner bearing for the tubular member 6.

To prevent the closure device 12 from moving outwardly, in the direction of its length, it has a shouldered part 12^a which engages the washer 60, as is clearly shown in Figure 2, by reference to which and to Figures 4 and 5 it will be observed that the magazine tube 4 has diametrically oppositely disposed projecting nibs 44 that fit into the elongated slots 31 in the sleeve 30 of the finger operated or turning cap 3, through which connection rotary movement is imparted to the tubular member 4, as the cap member is turned, as indicated in Figure 1.

The slot 16 in the closure device 12, through which the member 50 of the lead ejector passes, extends in spiral direction the full length of the tubular extension 12^b, so that a continued feeding of the ejector to the limit of its movement, either forwardly or backwardly, effects only one-fourth of a revolution of the closure device, as is best understood by referring to Figure 4, from which it will also be seen that a relatively quick turn is always imparted to the sleeve 30, as the member 3 is turned and the magazine of leads are constantly turned so, that, at practically all times, one of the lead carrying pockets is in radial position above the lead receiver 8, the ratio of movement of the parts, as shown in the drawing, being such that during the feed of the ejector backward, its full limit, the magazine will have made many complete revolutions, thereby passing all of the lead holding pockets in line with the receiver 8 and since the closure or cut off device makes but a one-fourth of a revolution during the complete backward or forward movement of the ejector 5, it follows that, when the plunger or ejector 5 is fed back to the limit of its movement, which is effected by a stop pin 17, a passage is provided for dropping the uppermost one of the leads shown in Figure 4 into the receiver in proper position for being fed out by the ejector 5 as reverse rotation is applied to the cap 3 and to insure a proper feed of the forward end of the lead, the receiver 8 has a tubular front end 85 into which the lead is directed, when fed forwardly, it being understood that from Figure 2, that the tubular end 85 of the lead receiver or holder 8 extends to the outlet

35 of the cap 3.

From the foregoing description taken in connection with the drawings, it is believed that the complete construction, the manner of its use and the advantages of my present 5 form of writing device will be readily apparent to those skilled in the art to which my invention relates.

The construction of the parts is comparatively simple and the several parts are 10 adapted for being readily and economically manufactured and easily assembled for use.

In my present invention, the user must first bring the parts into a predetermined adjustment before it will be possible to feed 15 another lead into the receiver in position for being engaged by the ejector element, which is done by simply turning the cap in reverse direction until it stops, at which time the closure device will have completed its one- 20 fourth revolution and opened the passage-way through which a lead may be dropped, its full length, into the receiver 8 and, after it has thus dropped into the receiver, it may be readily advanced through the cap end 3 25 to project the desired pencil point by forward or clockwise rotation of the cap 3.

What I claim is:

1. In a writing device of the character described, a casing having a pencil point 30 passage, a fixedly held pencil lead receiver from which the lead is passed through the point passage, a plunger cooperative with the said receiver, a magazine within the casing having a series of independent lead 35 carrying pockets that surround the receiver and from which the leads are individually dropped into the receiver, a closure device interposed between the receiver and the lead pockets having a passage through which a lead can pass from the pocket into the receiver and means for effecting rotation of the closure device for bringing its passage in register with the receiver and a selected one of the lead holding pockets. 40

2. In a writing device of the character described, a casing having a pencil point 45 passage, a fixedly held pencil lead receiver from which the lead is passed through the point passage, a plunger cooperative with the said receiver, a magazine within the casing having a series of independent lead carrying pockets that surround the receiver and from which the leads are individually dropped into the receiver, a closure device interposed between the receiver and the lead 50 pockets having a passage through which a lead can pass from the pocket into the receiver and means for effecting rotation of the closure device for bringing its passage in register with the receiver and a selected one of the lead holding pockets, the said magazine being mounted to rotate around the receiver. 55

3. In a writing device of the character described, a casing having a pencil point pas-

sage, a fixedly held pencil lead receiver from which the lead is passed through the point passage, a plunger cooperative with the said receiver, a magazine within the casing having a series of independent lead carrying 70 pockets that surround the receiver and from which the leads are individually dropped into the receiver, a closure device interposed between the receiver and the lead pockets having a passage through which a lead can pass from the pocket into the receiver and means for effecting rotation of the closure device for bringing its passage in register with the receiver and a selected one of the lead holding pockets, the said magazine being mounted to rotate around the receiver, and means operable externally of the casing for effecting rotation of the magazine and the closure device. 75

4. In a writing device of the character described, a casing having a pencil point passage, a fixedly held pencil lead receiver from which the lead is passed through the point passage, a plunger cooperative with the said receiver, a magazine within the casing having a series of independent lead carrying 80 pockets that surround the receiver and from which the leads are individually dropped into the receiver, a closure device interposed between the receiver and the lead pockets having a passage through which a lead can pass from the pocket into the receiver and means for effecting rotation of the closure device for bringing its passage in register with the receiver and a selected one of the lead holding pockets, the said magazine being mounted to rotate around the receiver, and means operable externally of the casing for effecting rotation of the magazine and the closure device. 85

5. A multiple pencil lead holder comprising a casing having a pencil point passage at its forward end, a relatively fixedly held pencil lead receiving tube axially located within and lengthwise of the casing from 90 which the pencil lead is passed through the pencil point passage in the casing, a plunger operable in the lead receiving tube, a magazine having a series of longitudinally extended radial pockets, each of which is adapted to receive a pencil lead and all of which center to drop their leads into the pencil receiver, a cut off interposed between the magazine pockets and the pencil receiver 95 adapted, when the lead plunger is returned to the limit of its backward adjustment, to open a passage between one of the magazine pockets and the lead receiver, and means operable externally of the casing for 100 simultaneously imparting a relatively slow 105

125

120

130

rotation to the magazine and rapid rotation to the cut off and move the plunger in the forward or backward direction.

6. A multiple pencil lead holder comprising a casing having a pencil point passage at its forward end, a relatively fixedly held pencil lead receiving tube axially located within and lengthwise of the casing from which the pencil lead is passed through the pencil point passage in the casing, a plunger operable in the lead receiving tube, a magazine having a series of longitudinally extended radial pockets, each of which is adapted to receive a pencil lead and all of which center to drop their leads into the pencil receiver, a cut off interposed between the magazine pockets and the pencil receiver adapted, when the lead plunger is returned to the limit of its backward adjustment, to open a passage between one of the magazine pockets and the lead receiver, and means operable externally of the casing for simultaneously imparting a relatively slow rotation to the magazine and rapid rotation to the cut off and move the plunger in the forward or backward direction, the said means including an internal screw feed, a screw engaging head on the plunger, and a tubular extension on the rotatable cut off that has a spirally directed slot with which the plunger head engages, as it is fed forwardly or backwardly by the screw feed.
7. A multiple pencil lead holder comprising a casing having a pencil point passage at its forward end, a relatively fixedly held pencil lead receiving tube axially located within and lengthwise of the casing from which the pencil lead is passed through the pencil point passage in the casing, a plunger operable in the lead receiving tube, a magazine having a series of longitudinally extended radial pockets, each of which is adapted to receive a pencil lead and all of which center to drop their leads into the pencil receiver, a cut off interposed between the magazine pockets and the pencil receiver adapted, when the lead plunger is returned to the limit of its backward adjustment, to open a passage between one of the magazine pockets and the lead receiver, and means operable externally of the casing for simultaneously imparting a relatively slow rotation to the magazine and rapid rotation to the cut off and move the plunger in the forward or backward direction, the said means including an internal screw feed, a screw engaging head on the plunger, and a tubular extension on the rotatable cut off that has a spirally directed slot with which the plunger head engages, as it is fed forwardly or backwardly by the screw feed.
8. A multiple pencil lead holder comprising a casing having a pencil point passage at its forward end, a relatively fixedly held pencil lead receiving tube axially located within and lengthwise of the casing from which the pencil lead is passed through the pencil point passage in the casing, a plunger operable in the lead receiving tube, a magazine having a series of longitudinally extended radial pockets, each of which is adapted to receive a pencil lead and all of which center to drop their leads into the pencil receiver, a cut off interposed between the magazine pockets and the pencil receiver adapted, when the lead plunger is returned to the limit of its backward adjustment, to open a passage between one of the magazine pockets and the lead receiver, and means operable externally of the casing for simultaneously imparting a relatively slow rotation to the magazine and rapid rotation to the cut off and move the plunger in the forward or backward direction, the said means including an internal screw feed, a screw engaging head on the plunger, and a tubular extension on the rotatable cut off that has a spirally directed slot with which the plunger head engages, as it is fed forwardly or backwardly by the screw feed.

ing a casing having a pencil point passage at its forward end, a relatively fixedly held pencil lead receiving tube axially located within and lengthwise of the casing from which the pencil lead is passed through the pencil point passage in the casing, a plunger operable in the lead receiving tube, a magazine having a series of longitudinally extended radial pockets, each of which is adapted to receive a pencil lead and all of which center to drop their leads into the pencil receiver, a cut off interposed between the magazine pockets and the pencil receiver adapted, when the lead plunger is returned to the limit of its backward adjustment, to open a passage between one of the magazine pockets and the lead receiver, and means operable externally of the casing for simultaneously imparting a relatively slow rotation to the magazine and rapid rotation to the cut off and move the plunger in the forward or backward direction, the said means including an internal screw feed, a screw engaging head on the plunger, and a tubular extension on the rotatable cut off that has a spirally directed slot with which the plunger head engages, as it is fed forwardly or backwardly by the screw feed, and an internally operated device cooperative with the casing for imparting rotation to the screw feed, said device comprising the tapered head of the casing having the lead opening through which the lead point is projected and which includes a sleeve workable within the casing and coupled with the screw feed, the latter comprising a tube having an internal screw way that is engaged by the plunger head.

9. In a writing device of the character stated, the combination of a casing, a cap closing one end thereof, the said cap being rotatably mounted with respect to the casing and provided with a central pencil point passage, a pencil lead receiver mounted axially of and extended lengthwise of the casing, the said retainer including a rearwardly extended longitudinally slotted sleeve, means for fixedly attaching the end of the sleeve to the casing, a tubular member rotatable within the casing about the pencil lead receiver, the said tubular member having an internal screw feed in the rear end thereof and a series of longitudinally extended and annularly disposed radial pockets that surround the pencil carrying portion of the receiver, a plunger cooperative with the receiver for movement in the direction of the length of the receiver, the said plunger having an upturned member that engages the internal screw feed, a closure device rotatable around the pencil point receiver, the said closure device including a longitudinally slotted front end whose slot is adapted, at times, to open a way from one of the lead magazine pockets, the full

length thereof, to the lead receiver and a diagonally slotted rear end through which the screw engaging or projected end of the plunger engages and a connection that joins the tubular member having the magazine and the screw feed with the cap rotatably mounted on the front end of the casing.

10. In a magazine pencil, a casing, a lead receiver in the casing having a longitudinal lead receiving slot and having a tubular end through which the lead received is fed, a lead ejector operating in said receiver, said casing enclosing a lead magazine chamber from which the leads drop into the receiver, a rotary gate controlling passage of the leads through the receiving slot into the receiver, and means for operating said ejector and said gate.

11. In a magazine pencil, a casing, a lead receiver in the casing having a longitudinal lead receiving slot and having a tubular end through which the lead received is fed, a lead ejector operating in said receiver, said casing enclosing a lead magazine chamber

from which the leads drop into the receiver, a rotary gate controlling passage of the leads through the receiving slot into the receiver, means operating said ejector and said gate to close the gate as the lead is fed forwardly in the receiver and open the gate when the ejector is retracted.

12. In a magazine pencil, a casing, a lead receiver in the casing having a longitudinal lead receiving slot and having a tubular end through which the lead received is fed, a lead ejector operating in said receiver, said casing enclosing a lead magazine chamber from which the leads drop into the receiver, a rotary gate controlling passage of the leads through the receiving slot into the receiver, means to hold said ejector against turning while allowing endwise movement thereof, a threaded barrel or tube to advance or retract said ejector and a device swivelly mounted on the end of said casing for turning said barrel or tube.

AMBROSE FLEMING.
